UNITED STATES PATENT OFFICE

2,417,960

BENT CORRUGATED WEB AND METHOD AND
MEANS FOR MAKING SAME

William A. Weightman, Philadelphia, Pa., assignor to The Budd Company, Philadelphia, Pa., a corporation of Pennsylvania

Original application March 31, 1939, Serial No. 265,161, now Patent No. 2,350,379, dated June 6, 1944. Divided and this application August 13, 1943, Serial No. 498,508

4 Claims. (Cl. 153—46)

1

The present invention relates to a method and to equipment primarily intended for the purpose of bending metal or the like and to bent articles.

More specifically, it relates to a method and tools for bending metallic or other profiles having grooves or channels into definite shapes which are predetermined by the machine itself in co-operation with the tools used therewith.

The new method and machine are designed for doing a great variety of bending work and are particularly useful in bending corrugated metal in a direction at an angle to the general longitudinal direction of the corrugations, specifically in producing an approximately cylindrical surface, whose elements are at right angles to the direction of the corrugations. The word "cylindrical" is used here in its broad mathematical sense to mean a curved surface generated by a line constantly intersecting a given curve, not necessarily circular, said line or element remaining always parallel to itself. It should, however, be noted that the machine is not restricted to cylindrical surfaces even of this very general type, but may produce conical surfaces and even warped surfaces; these surfaces being predetermined by the tools applied to the machine.

The invention will be understood clearly from the following specification descriptive of embodiments thereof, particularly upon referring to the accompanying drawings, wherein:

Fig. 1 is a plan view of the machine;

Fig. 2 is a section through the machine shown in Fig. 1 on the plane indicated by the line 2—2, looking in the direction of the arrows, the gearing being shown in elevation and the bending tools being omitted;

Fig. 3 is a vertical section, partly broken away and partly in elevation of the upper part of the machine and of the bending tools on a larger scale than Figures 1 and 2, the section being made on the planes indicated by the broken line 3—3 of Fig. 1;

Fig. 4 is a partly sectional vertical elevation of a means for clamping the workpiece, the section being made on the plane indicated by the line 4—4 of Fig. 1;

Fig. 5 is a fragmentary sectional view showing a portion of the die and of a cooperating bar-shaped tool with a workpiece being shaped between them, that is, a fragmentary section similar to part of Figure 3 but on a still larger scale; and

Fig. 6 is a perspective view of the workpiece.

While the drawings and the following specifi-

2

cation disclose many details of a bending machine, it should be understood that the general aspects of the machine and of the method form the subject matter of applicant's Patent No. 2,350,379, "Machine for Bending Metal," issued June 6, 1944, on application Serial No. 265,161, filed March 31, 1939, of which the present application is a division.

Referring first to Figs. 1, 2, 3 and 4, the table 1 is supported by means of the inclined struts or columns 2 and columns 2' secured to the base plate 3. The table top carries the pivot pin 6. An arcuate-annular member 10 may be supported in a substantially horizontal plane upon a set of flanges 11 carried by the struts 2 and by a series of vertical supports 12 so as to provide a firm foundation for the said annular arcuate member. Upon this member 10 may be mounted an arcuate rack member 13 having suitable teeth 14. A pinion 15 cooperates with the rack 13. A stationary shaft 16 supported in the base 3 at 17 in any suitable manner and secured against shifting by means of a suitable flanged support 18 secured to the table 1 may serve as the support 25 for various elements which will now be described.

A worm wheel 19 having a bevel pinion 20 secured thereto or integral therewith is mounted for rotation about the shaft 16 and is held in proper vertical position between the collar 21 and the arm 22 of a support so that the bevel pinion 20 will mesh properly with the bevel gear 23 carried by the shaft 24 upon which the pinion 15 is secured. The shaft 24 is journalled at one end in the support 26 and at the other end a bearing 27 carried by one end of an arm 28 which is pivoted about the shaft 16.

A worm 29 secured to the gear 30, meshes with the worm wheel 19 and the gear 30 meshes with the cooperating gear 31, the worm being mounted upon the shaft 32 while the gear 31 is mounted upon the shaft 33. Both ends of the shaft 32 and one end of the shaft 33 are journalled in suitable bearings in the bracket 34 which may be secured to the base 3 in any desired manner.

The shaft 33 has its remaining end journalled in a pedestal 36 and carries near this end a suitable pulley 37 which is connected by means of the belt 38 to the drive pulley 39 mounted on the shaft 40 of the motor 41.

The stud or pin 6 preferably has its lower end 50 screwed into the flanged supporting member 18.

Referring now more particularly to Fig. 2, it will be seen that the arm 28 carries the support 55 26 already mentioned, which may be secured

thereto in any desired way, for example by means of the cap screws 54. The arm 22 extending from the support 26 may have a suitable bushing, serving as a bearing for the central shaft 16 and the other arm 56 may likewise have a bushing therein also cooperating with the shaft 16. It will be clear that the bracket 34 also affords support to the shaft 16, which passes through bores formed in the lateral arms 60 and 61 extending from said bracket 34, and inasmuch as the shaft 16 does not rotate no bushings or other bearings are necessary here. The arm 61 also provides support for the lever 28, so that the lever 28 may be firmly supported and yet be free to rotate easily about the axis of the shaft 16. A suitable strut 69 provides a rigid brace between one end of the lever 28, and arm 56 of the bracket 26.

Thus when the shaft 40 of the motor 41 turns, it will transmit rotation through the belt 38 to the pulley 37, then through the shaft 33 to the gear 31, then to the gear 30 and the worm 29 which will cause the worm wheel 19 to rotate about the shaft 16, thereby turning the bevel pinion 20 which in turn rotates the bevel gear 23 as well as the pinion 15 secured to its shaft 24. It is clear that when the pinion 15 turns it must move along the arcuate rack 13 because the said rack is stationary and, therefore, the only motion possible is that of the bearing which supports the shaft 24. Since this is attached to the lever 28 it is clear that operation of the motor 41 will cause the lever 28 to rotate about the axis of the shaft 16. Because of the tremendous speed reduction ratio produced by the gearing described, it will be clear that a very great turning moment will be exerted by the lever 28 in its rotation so that it will have ample power to perform the bending operations dependent thereon.

A bifurcated bending yoke having the upper arm 87 and the lower arm 88 is pivotally held on the stub shaft or pin 6 which passes through holes. The yoke end 90 has a suitable bore therein to receive an operating rod 92 which preferably fits easily therein, said rod 92 also passing through a yoke 93 which is securable to the movable arm 28 in any suitable way, for example by means of the plate 94 and cap screws 95. The yoke end 90 carries, for a purpose to be described later on, adjusting screws or set screws 96.

The drawings show the machine set up to make bends of relatively short radius in relatively wide material and is particularly useful for bending corrugated metal as indicated at 102, although it may also be used for rods and tubes.

A clamping device indicated as a whole by reference character 103 is secured to the table 1 and this may be made as shown in Fig 4. A suitable bracket or yoke 104 having formed therein projections 105, corresponding to the corrugations of the workpiece, has a clamping member 106 also having projections thereon spaced alternately with the projections 105 so that the workpiece 102 will fit between members 104 and 105. The opposite side of the yoke 107 is preferably ribbed, as shown, for stiffness and has screws 108 threaded through suitable bosses 109, so that upon tightening the screws 108 the clamping member 106 will secure the workpiece 102 against the upright 104. The bracket 103 has a flange 110 at its lower end which may be suitably clamped to the table 1, as by the screws 111. This whole device, therefore, constitutes a vise or holding means which will securely clamp the corrugated metal 102 without bending it out of shape or mutilating it in any way.

The inner bending die 112 shown in Figures 3 and 5 consist of a circumferentially grooved cylindrical member, the grooves of which fit the corrugations of the workpiece 102. It is clear that when a piece of corrugated metal is bent, particularly about an inner bending die having a relatively small radius, there is a surplus of material at the portions of smallest radius and this material must be disposed of in order to prevent warping, tearing, or incorrect shaping of the bend.

This function is accomplished in a novel and extremely successful way by providing additional raised projections 113 at the centers of the grooves in the die 112 and, of course, corresponding grooves in the bending bar 114 which rests against the outer side of the corrugated metal, so that additional small corrugations are produced in the corrugated metal throughout the extent of the bend. The bar 114 is, of course, shaped properly to receive the corrugated metal workpiece between it and the die 112 and it will be understood that the supplemental relatively narrow corrugations produced by the ribs 113 serve to take up the surplus material at the innermost parts of the bend to prevent tearing, warping, etc. A roll 115 rotatably held in the U-shaped carriage member 116 by means of the shaft or pin 117 bears against the outside of the bending bar 114. The bifurcated bending yoke consisting of the arms 87 and 88 pivoted about the pin or shaft 6 is moved about said pivot by means of the operating rod 92, passing through the yoke 93 secured to the arm 28 and the said roller 115 is adjusted in a radial direction by the screws 96 to conform to the material being bent.

Reference to Figures 5 and 6 will show more clearly the relative shapes of the bending die 112 and the bar 114 with the workpiece 102 between them and of the workpiece alone, respectively. The supplemental corrugating ribs are shown at 113 and the corresponding grooves in the bar are indicated at 118. It will be clear that considerable strains must be supported by the upper or remote end of the pivot shaft 6 and in order to brace the said upper end thereof suitable angularly arranged struts 119 may be provided. These in the form illustrated consist merely of a single piece having two arms 119 arranged at an angle to one another and having a bore 120 at one end to receive the pin 6, while the lower end of each bar 119 is secured to the table 1 by a screw or bolt 121. It will be noted that the arms 119 extend toward the front of the table and thus are kept out of the way of the workpiece and of the tool for bending the same.

When the workpiece is to be bent into a curve which is not a circle or a circular arc, that is, where the radius of curvature varies, it is clear that provision must be made for moving the outer bending die or follower radially in or out in conformity with the shape of the inner bending die.

While a specific form of the invention is disclosed, it will, of course, be understood that this is done purely by way of illustration and not in any limiting sense.

It is believed that the operation of the device will be understood from the description of the structure, however, it may be briefly summarized as follows:

The corrugated metal workpiece 102 is suitably clamped in the end clamp or vise 103 so as to maintain its end portion rigidly held to the table and thereupon the yoke carrying the roller 115 is adjusted to the proper position to force the

bending bar 114 against the outer surface of the workpiece 102, the inner surface being engaged against the grooved inner bending die 112. When the bending arm 28 is set into rotation by the motor 41 and intermediate mechanism, the roller 115 will maintain the bar 114 in close contact with the outer surface of the workpiece while the lever 28 is turning, the result being that a bend of the desired extent and nature is imparted to the workpiece and, furthermore, additional small corrugations are formed at the location of the bend by means of the ridges 113 on the inner bending die 112 for the purpose of taking up the surplus metal as already mentioned. This, moreover, gives an ornamental and workmanlike appearance to the bend and very satisfactorily solves the problem of accommodating the excess metal at the interior of the bend which would otherwise cause difficulty because of lack of accommodation for the same and might produce wrinkled, folded, or torn bends.

By securing the vise 103 at a new location on the table top it is, of course, possible to continue the bending beyond its original extent so that even hairpin bends may be made if desired, that is, the far end of the corrugated metal may be bent back substantially into parallelism with its initial portion.

It will be understood that the machine and the outlined method are capable of many modifications in order to accommodate the various types of workpieces and that workpieces which consist of corrugated metal and which are of varying heights and cross-sections, may be successfully bent into a large variety of shapes, since the machine provides ample capacity and power for the most varied range of bending work. It will be clear that all such forms may be bent with equal success by providing merely the proper shapes of inner bending dies and outer bending bars to cooperate therewith and that in every instance there is no sliding or rolling of the outer bending member, that is of the roller against the material itself, so that no scratching or scoring of the workpiece will take place, since the roller does not come in contact with the workpiece during the bending operation.

The novel features of the invention are defined in the following.

What is claimed is:

1. The process of bending corrugated metal which consists in applying companion bending tools, substantially fitting the corrugations, on opposite sides of the corrugated metal, and pro-

ducing relative bending motion between the metal and the tools, while simultaneously forming additional corrugations of relatively small amplitude in the metal at the innermost parts on the inside of the bend, to accommodate the excess metal and thus prevent injury and warping.

2. Means for bending corrugated metal comprising an inner bending die having its working surface grooved circumferentially to fit the corrugations of the workpiece and a complementary outer bending die substantially fitting thereagainst, one of the said bending dies having supplemental ridges formed on the portions of the working surface adapted for engagement with the bottoms of the grooves of a workpiece on the inner side of the bend, and the other die having corresponding supplemental grooves to receive said ridges, whereby additional corrugations will be formed in the bend of the workpiece and the surplus metal in the bottoms of the main corrugations taken up by said additional corrugations thereby avoiding formation of wrinkles in the walls of the main corrugations during the bending operation.

3. A corrugated web cold bent transversely to the direction of the main corrugations and having formed therein on the concave side of the curvature secondary corrugations of relatively small amplitude which extend in the same direction as the main corrugations, such secondary corrugations accommodating the excess material incident to the shortening of the web on the concave side under the compression during the cold bending whereas the convex side of the web is free from corresponding secondary corrugations.

4. A cold bent corrugated web according to claim 3 having said secondary corrugations projecting radially outwardly away from the center of the curvature.
